SPARK PLUG

Armen A. Kasarjian, Jackson Heights, Long Island, N. Y.

Application September 9, 1933, Serial No. 688,710

4 Claims. (Cl. 123—169)

This invention relates to spark plugs and is directed more particularly to a plug so constituted as to have longer useful life as well as longer continuous life between overhauls. This is accomplished by making the sparking areas 5 of the electrodes as large as practicable.

The spark gaps of all spark plugs without any exception gradually increase by use due to erosion of the electrode material at the sparking 10 surfaces. The erosion is thought to be due to charged particles or molecules thrown out of the electrodes with each spark. The voltage impressed on the spark plugs and therefore the sparks, being oscillatory in character both the 15 center and the ground electrodes are subject to erosion.

The rate of erosion is affected by the temperature of the electrodes; the higher the temperature of the electrodes, the higher is the rate 20 of erosion. In the case of aviation engines, especially in the high compression air-cooled types, the erosion is so rapid that frequent resetting of the spark gaps is necessary. Electrodes made of heat-resisting metals resist the erosion somewhat; however, with the present design of electrodes, the life of spark plugs between overhauls 25 is still considered too short.

Heretofore the electrodes of most of the spark plugs were made in the shape of pins. The tip areas (surfaces perpendicular to the axes of the pin) of the ground electrode against the side of the center electrode, or vice versa, are used 30 as sparking surfaces. Some of the spark plugs have the sparking surfaces of the ground electrodes rectangular in shape. None of them, however, possesses sufficient sparking area to give 35 the desired long life, and, at the same time, have the gaps easily measured and reset.

The primary purpose of the present invention 40 is to produce spark plugs possessing sufficient long life as to require no attention and no resetting of the spark gaps before the engine in which they are used is ready for overhaul.

The longer life of the subject plug is obtained 45 by making the sparking areas of the electrodes much larger than it has been the practice heretofore. The center electrode of this plug is made conical in shape and the sparking area of the ground electrodes is shaped to conform to the 50 contour of the cone of the center electrode. The sparking areas of the electrodes are limited only by the lateral surface of the center electrode, as shown in Figs. 1 to 3.

Features of the invention, other than those 55 adverted to, will be apparent from the herein-

after detailed description and claims when used in conjunction with the accompanying drawing.

The accompanying drawing illustrates the practical embodiment of the invention but the construction therein shown is to be understood 5 as illustrative only, and not definitive of the limit of the invention.

Figure 1 is a cross section of a spark plug showing one form embodying the present invention.

Figs. 2 and 3 show the preferred form in which 10 the full length of the conical surface of the center electrode is utilized for sparking and the cup is cut out into four wide prongs.

Figs. 4 and 5 illustrate a modification in which 15 a long and narrow form of ground electrode is used with the conical center electrode.

Figs. 6 and 7 show a somewhat wider form 20 of ground electrode.

The plug structure of this invention may be included in any conventional plug construction 25 so far as the porcelain, mica, or basic structure is concerned. However, for the purpose of illustration, I have shown the same in the drawing as incorporated in a well known spark plug of the aviation type.

In the accompanying drawing, 5 designates 25 the shell of the plug, provided with various types of ground electrodes. 1 designates the spindle head which has been referred to as the center electrode. It is shown as a frustum of a cone 30 in shape with more or less flattened vertex. This shape offers a large sparking area and facility for inspection and adjustment of spark gaps.

2 is the preferred form of the side or the ground electrode. It may be made like a cup 35 with a hole in the middle to receive the center electrode. The curvature of the depression of the cup is identical with that of the center electrode, so that the distances (spark gaps) between any sparking point on the cone of the side electrode and its corresponding point on the center electrode are practically equal. The lateral height of the cone of the side electrode may be equal to, greater than or smaller than 40 that of the center electrode cone. This invention may be carried out in practice by several forms of ground electrodes, some of which are 45 enumerated hereafter; for example:

A. As a cup as shown in Fig. 1 of any desired 50 depth or height.

B. As a cup cut out to form four wide prongs or leaves as shown in Figs. 2 and 3.

C. As a bar, rectangular or round and attached 55 to the shell in any suitable manner as shown

e. g. in Figs. 4 and 5, there being one or more of these bars used in a plug.

5 D. As a part of a cup in the form of a prong or leaf as shown in Figs. 6 and 7, there being one or more of these leaves serving as side or ground electrodes.

10 When a plug, constructed in accordance with this invention is firing in an engine the spark first is across the smallest distance between the center electrode and the side electrodes following the path of least resistance. The spark continues in this path until the gap resistance of this path, due to process of erosion, becomes larger than that of another path. The spark will 15 then jump across the least resistance again. This process will continue until all the possible "proper" spark gaps have higher resistance than that of some "parasitic" gap either in the plug or in the ignition system. The plug will then 20 become inoperative. The plugs will then have to be taken out and the proper spark gaps reset closer to desired value.

25 The resetting of the proper spark gaps is accomplished by a tool specially constructed for the purpose. This tool pushes the side electrodes inwardly over the center electrode to the desired amount to produce the proper gap distance. In the case of the solid cup form, the electrode is pressed to the desire depth in a tight fitting 30 bore of the spark plug shell, whereas in the case of the bar or leaf forms of electrodes, they may be bent near their base to properly space them from the center electrode.

35 On account of the large area of sparking surfaces a much longer service is obtained from this plug with each setting of the gap than from plugs with conventional electrodes.

40 The lateral surface of a cone is not the largest surface obtainable. A spherical surface, concave, or convex, will give larger area. The inspection of the spark gaps, however, or resetting of the gaps with desired precision will be very difficult with the spherical gaps while with the cone shape no difficulty will be experienced.

45 The plug of the present invention in any of the ways which I have described it has proven to operate with marked efficiency as compared with plugs designed in accordance with prior practices. It possesses unusually long life. The 50 life of the plug of this construction on the average is three times the life of the plugs with conventional type of electrodes. These plugs have proven to possess such a long life that they required no attention before the engine in which they were operating was ready for overhauling.

55 In the accompanying drawing, I have illustrated the preferred form, and its variations, of the present invention. Having thus fully described the invention, what I claim as new and desire to secure by Letters Patent is:

1. A spark plug with electrodes having a large area of sparking surfaces composed of a center electrode having a surface, the intersection of which with any plane passed thru the axis of the plug is a straight line, and a side electrode 5 having a similar surface spaced from the first surface a distance substantially equal to the desired spark gap.

2. In a spark plug, a centre electrode having a frusto-conical head; a ground electrode bar 10 attached to the spark plug shell opposite the base of the head and extending therefrom toward the head to a distance equivalent to the spark gap from the surface of the head, from where it extends in a straight line parallel to 15 the surface of the conical head.

3. A spark plug having a shell, a central electrode with a cone shaped head having a sparking surface, the intersection of which with any plane extending longitudinally of said central 20 electrode head through the axis thereof is a straight line, and a set of stout prongs united with the lower end of the shell and constituting grounded electrodes, said prongs having sparking surfaces lying opposite the sparking surface 25 of the central electrode head, and being so formed that the intersection of any of said surfaces with any plane passing longitudinally of said central electrode head through the axis thereof is also a straight line, so that there is a 30 deep and large spark gap surface area between the central and grounded electrodes, which said gap may easily and accurately be measured by a narrow strip or wire gauge feelers, with a large section in the grounded electrodes to carry 35 off heat into the shell, the grounded electrodes being adjustable by deflecting their down turned portions inward, so that in such adjustment the large spark gap surface area may be maintained.

4. A spark plug having a shell, a central electrode with a cone shaped head having a sparking surface, a set of stout prongs united with the lower end of the shell and constituting grounded electrodes, said prongs having sparking surfaces lying opposite the sparking surface of the central electrode head, the intersection of the said 40 sparking surfaces of the central electrode head and the grounded electrodes, respectively, with any plane passing longitudinally of said central electrode head through the axis thereof being 45 parallel straight lines, so that there is a deep and large spark gap surface area between the central and grounded electrodes, which said gap may easily and accurately be measured by a narrow strip or wire gauge feelers, with a large section in the grounded electrodes to carry off 50 heat into the shell, the grounded electrodes being adjustable by deflecting their down turned portions inward, so that in such adjustment the large spark gap surface area may be maintained. 55
